United States Patent Office.

CHARLES F. ANNAN, OF BOSTON, ASSIGNOR TO HIMSELF AND HERBERT S. MERRILL, OF CAMBRIDGE, MASSACHUSETTS.

Design No. 4,503, dated December 13, 1870.

DESIGN FOR A FRAME FOR A PAPER-BAG MACHINE.

The Schedule referred to in these Letters Patent and making part of the same.

To all whom it may concern:

Be it known that I, CHARLES F. ANNAN, of Boston, in the county of Suffolk and State of Massachusetts, have invented and produced a new and original Design for the Frame-work of a Machine for Making Paper Bags, of which the following is a full, clear, and exact description, reference being had to the accompanying photographs making part of this specification, in which—

Figure 1 is a perspective view of a machine for making paper bags provided with frame-work of my improved design.

Figure 2 is an elevation of the sides of the frame-work.

My invention consists in a unique and ornamental design for the frame-work of a machine for making paper bags, in which economy of space, strength, and lightness are combined with cheapness of construction, while convenient and secure places are afforded for the bearings of the shafts, rolls, &c., and easy access is obtained to the interior of the machine.

In the photographs—

A B represent the upper and lower portions of one side of the frame-work, at one end of which is a vertical portion, C.

Between the portions A B are circular portions D E, within one, E, of which are two curved braces, a b, in which are bearings for shafts.

At one end of the frame-work is a brace, G, of the form shown, at the end of which is the bearing for

one end of the shaft which supports the roll of paper from which the bags are formed.

On the top of the portion A is a rectangular frame, H, within which is a bar or brace, c, in which are formed the bearings of the upper feed-rolls of the machine.

A frame-work of the design above described is unique and ornamental, and is particularly adapted to machines for making paper bags, as it enables me to arrange the mechanism much more compactly than heretofore, the combination of the circular portions D E and braces a b with the straight portions A B C enabling me to construct a frame-work with much less metal than has heretofore been required, while economy of space, strength, stiffness, and lightness are combined with cheapness of construction, convenient and secure places are afforded for the bearings of the shafts, rolls, &c., and easy access is obtained to the interior of the machine.

Claim.

What I claim as my invention, and desire to secure by Letters Patent, is—

The design for the frame-work of a machine for making paper bags herein shown and described.

Witness my hand this 26th day of November, A. D. 1870.
